DESIGN FOR A SEWING MACHINE SPOOL HOLDER

Eugene Arnold, Torrington, Conn.

Application February 28, 1935, Serial No. 55,656

Term of patent 3½ years

To all whom it may concern:

Be it known that I, Eugene Arnold, a citizen of the United States and residing at Torrington, in the county of Litchfield and State of Connecticut, have invented a new, original, and ornamental Design for Sewing Machine Spool Holders, of which the following is a specification, reference being had to the accompanying drawing, forming part thereof.

Fig. 1 is a perspective view of the ornamental spool holder showing my new design.

Fig. 2 is a top plan view of the same on a reduced scale.

I claim:

The ornamental design for a sewing machine spool holder, as shown.

In testimony whereof, I have affixed my signature to this specification.

EUGENE ARNOLD.
